(57) **ABSTRACT**

A new and distinct variety of miniature rose plant, referred to by its cultivar name, 'KORpot120', is described. The new variety forms in abundance on a substantially continuous basis attractive, orange-colored blossoms. The vegetation is vigorous, and the growth habit is compact. Attractive semi-glossy foliage is formed. Additionally, the new variety is particularly well suited for growing as distinctive ornamentation in the landscape.

1 Drawing Sheet

1

Latin name of genus and species of plant claimed: *Rosa hybrida*.

Variety denomination: 'KORpot120'.

STATEMENT REGARDING PRIOR
DISCLOSURES BY THE INVENTOR

The first offer for sale of the new variety was November 2021, in Germany. The first offer for sale of the new variety was by the inventor or another who obtained the new variety directly or indirectly from the inventor. No plants of the new variety have been sold in this country or anywhere in the world, nor has any disclosure of the new plant been made, more than one year prior the effective filing date of this application, and such sale or disclosure within one year was either derived directly or indirectly from the inventor.

BACKGROUND OF THE INVENTION

The new variety of miniature rose plant of the present invention was created by controlled breeding in 2017 at Offenseth-Sparrieshoop, Germany by artificial pollination wherein two parents were crossed which previously had been studied in the hope that they would contribute the desired characteristics. The female parent (i.e., the seed parent) of the new variety was an unnamed breeder seedling (not patented). The male parent (i.e., the pollen parent) of the new variety was the 'RULD155a' variety (not patented).

2

The parentage of the new variety can be summarized as follows:

Unnamed Breeder Seedling x 'RULD155a'

5 The seeds resulting from the above pollination were sown and small plants were obtained which were physically and biologically different from each other. Selective study resulted in the identification of a single plant of the new variety.

10 The new variety has been found to undergo asexual propagation at Klein Offenseth-Sparrieshoop, Germany by a number of routes such as vegetative cuttings. Asexual propagation techniques in Klein Offenseth-Sparrieshoop, Germany, such as vegetative cuttings, have shown that the characteristics of the new variety are homogeneous, stable, and strictly transmissible by such asexual propagation from one generation to another. Accordingly, the new variety undergoes asexual propagation in a true-to-type manner.

SUMMARY OF THE INVENTION

It was found that the new variety of miniature rose plant of the present invention possesses the following combination of characteristics:

- (a) forms attractive, orange-colored blossoms,
- (b) exhibits a compact growth habit, and
- (c) forms vigorous vegetation.

The new variety well meets the needs of the horticultural industry. It can be grown to advantage as attractive ornamentation in parks, gardens, public areas, and residential landscapes. Accordingly, it is particularly well suited for growing in the landscape.

The new variety can be readily distinguished from its ancestors. More specifically, the unnamed breeding seedling female parent (i.e., the seed parent) displays a smaller flower size compared to the new variety. Additionally, the new variety provides a larger growth habit compared to the 'RUIld155a' variety (i.e., the pollen parent). Moreover, the new variety can be readily distinguished from non-parental related similar varieties. For example, 'KORpot021' (U.S. Plant Pat. No. 24,207) displays more petals and a less round flower shape compared to the new variety.

The new variety has been named the 'KORpot120' variety.

BRIEF DESCRIPTION OF THE PHOTOGRAPHS

The accompanying photograph shows, as nearly true as it is reasonably possible to make the same in a color illustration of this character, a typical specimen of the new variety and blossoms of the new variety. The illustrated rose plant of the new variety was approximately twelve weeks of age and was grown indoors on its own roots in 10.5 cm containers in Odense, Denmark.

Drawing—illustrates a specimen of the plant displaying flowers at varying points of opening.

DETAILED BOTANICAL DESCRIPTION

The chart used in the identification of colors is that of The Royal Horticultural Society (The R.H.S. Colour Chart, 2015 edition). The terminology which precedes reference to the chart has been added to indicate the corresponding color in more common terms and The R.H.S. Colour Chart designation used herein represents the closest color observed on the majority of the specified botanical feature. The description is based on two-years-old specimens of the new variety, observed during September, while growing in a 3-gallon container on its own roots in a greenhouse in Cochranville, Pennsylvania.

Botanical classification: *Rosa hybrida* cultivar 'KORpot120'.

Commercial classification: Miniature Rose.

Plant:

Habit.—Compact.

Height.—Approximately 36.0 cm on average from the top of the soil plane in 3-gallon pot.

Width.—Approximately 42.0 cm on average.

Branches:

Stems.—Color: young stems are commonly Green Group 143A; old wood is commonly Yellow-Green Group 146A. Length: Main stems: approximately 36.0 cm on average. Secondary stems: approximately 15.0 cm on average. Diameter: Main stems: approximately 8.0 mm on average. Secondary stems: approximately 3.0 mm on average. Texture: Glabrous.

Thorns.—Young Thorns: Amount: Moderate and very small. Color: commonly Greyed-Orange Group 165B. Size: Length: approximately 4.0 mm on average. Width: approximately 1.0 mm at point of attachment.

Foliage:

Color (young foliage).—Upper Surface: commonly Green Group 137A with indistinguishable venation. Under Surface: commonly a blend of Green Group 138B and Greyed-Orange Group 176C with venation of Yellow-Green Group 146C.

Color (old foliage).—Upper Surface: commonly Green Group 139A with indistinguishable venation. Under Surface: commonly Green Group 138B with venation of Green Group 139C.

Leaf margin.—Serrate.

Leaflets.—Number: 3, 5, and 7. Shape: Ovate. Apex: Acute. Base: Rounded. Arrangement: Odd-pinnate. Texture: Upper Surface: Smooth. Under Surface: Smooth. Venation pattern: Reticulate. Glossiness of upper side of leaf: Semi-glossy. Size: Terminal Leaflet. Length: approximately 4.0 cm on average. Width: approximately 2.8 cm on average. Lower Leaflets. Length: approximately 3.0 cm on average. Width: approximately 2.5 cm on average. 5-Leaflet leaf. Length: approximately 8.0 cm on average. Width: approximately 6.0 cm on average. Undulation of leaf margin: Slight.

Petiole.—Length: approximately 2.0 cm on average. Diameter: approximately 2.0 mm on average. Texture: Upper surface: Smooth. Under surface: Mostly smooth with sparse prickles. Color: Upper surface: commonly Yellow-Green Group 146B. Under surface: commonly Yellow-Green Group 146C.

Rachis.—Length: approximately 4.0 cm on average. Diameter: approximately 2.0 mm on average. Color: Upper surface: commonly Yellow-Green Group 146B. Under surface: commonly Yellow-Green Group 146C.

Stipules.—Length: approximately 7.0 mm on average. Width: approximately 2.0 mm on average. Margin: Entire to erose. Color: Upper surface: commonly Yellow-Green Group 146B. Under surface: commonly Yellow-Green Group 146C.

Inflorescence:

Number of flowers.—About 8 blooms on average on a plant at once.

Number of blossoms per stem.—Typically, 1 to 3 blooms per stem on average.

Peduncle.—Color: commonly Yellow-Green Group 146B. Diameter: approximately 3.0 mm on average. Length: approximately 3.0 cm on average. Surface Texture: Glabrous. Strength: Strong.

Sepal.—Number: 5. Upper surface color and texture: Covered in short pubescence, commonly Green-Group 143B. Under surface color and texture: Puberulent, commonly Green Group 143B. Size: Length: approximately 1.5 cm on average. Width: approximately 1.0 cm on average. Margin: Entire with occasional extensions on two or three sepals measuring approximately 7.0 mm in length and approximately 2.0 mm in width. Shape: Lanceolate. Apex: Acute to Aristate. Base: Truncate or flat as it joins the receptacle.

Buds.—Shape: Ovoid. Size: Length: approximately 2.5 cm on average. Width: approximately 2.0 cm on average. Color (when opening): commonly Orange Group 24A.

Flower.—Form: Double, cuplike. Diameter: approximately 6.0 cm on average. Height: approximately 3.0

cm on average. Profile: Flat. Duration: On the plant approximately 27 days. Fragrance: Very light sweet Fragrance.

Petal.—Color when first and fully open: Upper Surface: commonly Red Group 37B with basal spot of White Group 155B. Under Surface: commonly Red Group 37D with basal spot of White Group 155B. Color when fading: Upper and Under Surface: commonly Red Group 36C with a hint of Red Group 39B. Petal Texture of upper and lower surfaces: 5 Glabrous. Petal Margin Undulation: Moderate. Petals reflex one by one: Yes. Petal number: 60 on average. Petal drop: Average for the type. Length: Inner Petals: approximately 1.3 cm on average. Outer Petals: approximately 3.2 cm on average. 10 Width: Inner Petals: approximately 8.0 mm on average. Outer Petals: approximately 3.0 cm on average. Overall Shape: Broadly obovate. Margin: Entire. Apex Shape: Rounded to cuspidate. Base Shape: Rounded to cuneate.

Petaloids.—Number: On average, 5 per flower. Color: Upper and under surfaces: commonly Orange Group 24A with basal spot of Yellow Group 4D. Length: 15 Approximately 5.0 mm on average. Width: Approximately 3.0 mm on average. Texture: Smooth. Margins: Variable, entire to erose. Shape: Rounded and mostly curving inward. Apex: Round. Base: Cuneate.

Stamen.—Number: Approximately 80. Anthers — Number: Approximately 80. Color: commonly Yellow Group 11C. Shape: Oval. Length: Approximately 1.5 mm on average. Filaments — Length: 20 Approximately 1.5 mm on average. Color: commonly Green-Yellow Group 1B.

Pistils.—Arrangement: Separate and free. Number: 30 Approximately 96. Style: Color: commonly Green-Yellow Group 1B at the base, transitioning to Orange 25

Gorup 24A at the apex. Length: Approximately 5.0 mm on average. Stigma: Color: commonly Green-Yellow Group 1B. Diameter: Less than 1.0 mm. Shape: Fan Shaped.

Receptacle.—Diameter: approximately 5.0 mm on average. Depth: approximately 7.0 mm on average. Shape: Urn shaped. Color: commonly Yellow-Green Group 146C. Surface Texture: Smooth.

Pollen.—None observed.

Hips/seed formation.—None observed.

Development:

Vegetation.—Dark Green, vigorous, and strong.

Blossoming.—Abundant and continuous. Blooms may continue year-round if grown inside a warm greenhouse.

Hardiness.—Unknown.

Resistance to diseases.—Good resistance to Powdery Mildew (*Sphaerotheca pannosa*) disease under normal greenhouse growing conditions in Cochransville, Pennsylvania.

The new 'KORpot120' variety has not been observed under all possible environmental conditions to date. Accordingly, it is possible that the phenotypic expression may vary somewhat with changes in light intensity and duration, cultural practices, and other environmental conditions.

I claim:

1. A new and distinct variety of miniature rose plant named 'KORpot120' characterized by the following combination of characteristics:

- (a) forms attractive, orange-colored blossoms,
- (b) exhibits a compact growth habit, and
- (c) forms vigorous vegetation;

substantially as herein shown and described.
